UNITED STATES PATENT OFFICE.

HARRY V. GOULD, OF BRIDGEPORT, CONNECTICUT.

CABLE CONNECTER FOR OUTLET BOXES.

Application filed January 12, 1927. Serial No. 160,595.

My invention refers to cable connectors, for use in joining electric cables to cable boxes, switch boxes, outlet boxes and the like.

- 5 The purpose of the invention is to provide a simplified and improved form of cable connector which will be relatively light in weight and can be manufactured from cast metal at a comparatively low cost. Further to provide a connector having a series of extended points or bearings for engagement by the threading dies, so that the connectors may be readily and uniformly threaded and finished without any liability 10 of breaking the dies when threading the body portion of the connector. Also to provide a connector which will be properly and uniformly positioned within the box when secured thereto by lock nut.
- 20 I further provide an improved form of nut for use in connection with the before mentioned threaded portion of the connector and adjacent to the inner side of the box, which can be readily set up or loosened by 25 the assistance of a screw driver, chisel or other form of small hand tool, and where the use of a wrench would be prohibited by reason of the limited amount of space within the box.
- 30 With these and other objects in view, the invention resides and consists in the construction and novel combination and arrangement of parts hereinafter more fully described, illustrated in the accompanying 35 drawings, and pointed out in the claim here-to appended, it being understood that various changes in the form, proportion, size, and minor details of construction within the scope of the claim may be resorted to without departure from the spirit, or sacrificing 40 any of the advantages of the invention.

Similar characters of reference denote like or corresponding parts throughout the several figures of the accompanying drawing forming a part of this specification and upon which:

Fig. 1 shows a side elevation of a metal connector box having one of my improved cable connectors positioned therein, together with a short piece of electric cable, secured within the cable connector.

Fig. 2 is a cross sectional view taken on line 2—2 of Fig. 1.

Fig. 3 is a detached side view of one of my improved cable connectors, the nut being omitted.

Fig. 4 is an inner end view of the connector shown in Fig. 3; and,

Fig. 5 shows a detached perspective view of the nut employed for securing the cable 60 connectors in position in the holes of the box.

Referring in detail to the characters of reference marked upon the drawings, 10 represents a commercial form of a metal cable 65 box having suitable screw holes 11 positioned therein, and round pressed-in portions 12, which may be knocked out to form holes in which the cable connectors are positioned. 13—13 represents in-turned ears in 70 which are positioned suitable binding screws 14.

The connector proper is preferably formed of cast iron and comprises an elongated cylindrical member 15 having a central longitudinal opening 16 therein, the inner end portion of said opening being slightly contracted as at 17 to form an annular shoulder against which the flexible metal casing 18 of the cable 19 abuts. The connector further includes an outer annular rib or flange 75 portion 20, from the inner side of which projects points 21 that form footings to engage the outer face of the connector box immediately adjacent the holes. These 80 points also serve in the manufacture of the connectors as a means against which the threading dies are fed and stopped in the threading operation, to limit the cut in a manner to prevent breakage which is liable 85 to occur if the dies are fed direct against the flange.

The outer end portion of the connector is for the most part cylindrical in form, though includes an outer flat surface 22 in 90 which is positioned a set screw 23 for engagement with a side portion of the cable so as to readily bind the same as indicated in Fig. 2, to hold it in position. The inner cylindrical portion of the connector, is provided with a peripheral thread 24 which extends from the outer end to the flange 20, and in practice serves to enter the hole in the box, and to receive the special form of clamping nut 25, which is positioned upon 100 the thread and against the inner wall of the box in a manner to secure the connector in position. The nut 25 is provided in its corner portions, with notches forming shoulders against which the blade of a 105 screw driver may be positioned so that when the handle of the screw driver is hit the nut

will be turned to tighten or loosen it upon the threaded portion of the connector and in a way to more firmly engage or release the connector box.

5 This construction provides a practical and efficient form of connector which can be firmly secured to connector boxes in a manner to reliably hold an armored cable without its coming loose and pulling out, with the 10 adjustment or repositioning of the cables.

Having thus described my invention, what I claim and desire to secure by Letters Patent is:

A cable connector comprising a cylindrical sleeve, an external annular flange intermediate its ends and including a series of pointed projections formed upon one side of said flange, threads upon the outer periphery of one end portion of said sleeve adjacent said points, a nut fitted upon the threads, and means upon the other end of said sleeve for clamping a cable.

Signed at Bridgeport in the county of Fairfield and State of Connecticut this 10th day of Jan. A. D. 1927.

HARRY V. GOULD.
